UNITED STATES PATENT OFFICE

GEORGE W. O'KEEFFE, OF MILTON, MASSACHUSETTS, ASSIGNOR TO CONDIT ELECTRICAL MANUFACTURING CORPORATION, OF SOUTH BOSTON, MASSACHUSETTS, A CORPORATION OF MASSACHUSETTS

REMOTE CONTROL SWITCH

Application filed June 27, 1928. Serial No. 288,725.

This invention relates to push-button electric switches for the remote control of electrical apparatus, and especially for the control of electrically operated motor-starting switches, and has for an object the provision of a simple and reliable push-button switch of this type which is compact and economical to manufacture.

Push-button switches of this general type usually comprise a pair of normally open contacts, one of which is movable into engagement with the other to close the circuit of the apparatus, and a second pair of normally closed contacts, one of which is movable out of engagement with the other to effect the opening of the circuit of the apparatus to be controlled. The movable contact members are biased into open and closed positions respectively by spring means and are moved against the bias of the spring by means of their respective push buttons. In some instances it has been the practice to locate the contact biasing spring at the pivotal point of the movable contact members, the spring usually comprising a coil spring disposed around the pivot itself. Since this arrangement does not provide a strong biasing force to urge the contact members into and out of engagement it has been the general practice to use abutment contacts to avoid any friction between the cooperating contacts, although for other reasons the frictional and wiping engagement of the contact is much to be desired.

It is therefore an object of the invention to provide a push-button switch having contacts adapted to make frictional engagement with each other and biasing means for the movable contacts thereof having sufficient mechanical advantage to move the contacts into and out of wiping engagement with their cooperating fixed contacts.

A further object is the provision of a pair of independently movable switch arms having a common compression spring for hold-

ing them yieldingly in predetermined positions, and wherein the spring is supported internally in operative position by the arms.

Another object of the invention is the provision of a circuit controller of the push-button type having a pair of oppositely-extended circuit-controlling arms which are supported side by side on a common pivot and are independently movable thereon and have a biasing spring which is extended across the pivot and is connected with both arms for maintaining them yieldably in predetermined positions.

A yet further object is the provision of a switch or circuit controller of the above type and an insulating support and an enclosing casing therefor that is cheap to manufacture and easy to assemble.

It is a further object generally to improve the construction of push-button electric switches.

Fig. 1 is a front elevation of an electric switch embodying the invention with the cover largely broken away.

Fig. 2 is a side elevation of the switch of Fig. 1, taken along line 2—2 of Fig. 1, and showing the parts of the switch in their normal or unoperated positions.

Fig. 3 is a sectional view taken on lines 3—3 of Fig. 2.

Fig. 4 is a perspective view of the insulating supporting base for the switch.

Fig. 5 is a perspective view of the movable switch assembly.

Fig. 6 is a detail of a movable switch member.

Fig. 7 is a perspective view of the terminal supporting member for the movable switch members.

Fig. 8 is a perspective view of the supporting frame for the switch by which it is secured in its enclosing casing.

Fig. 9 is a wiring diagram of a typical circuit employing the switch embodying the invention for the control of an electric motor.

The switch embodying the invention, as shown herein for purposes of illustration, is utilized for the remote control of a motor and comprises two push-button control switches, one a normally open switch A for starting the motor and the other a normally closed switch B for stopping the motor. The switches are enclosed in a metal casing 10 having a cover 12 which provides a removable closure for the open front thereof; and the various parts 5 of the switch assembly are mounted as a unit on an insulating base. Said base, as shown in Fig. 4, comprises a substantially rectangular insulating body 14, preferably moulded to 10 the shape illustrated, having integral outstanding terminal-supporting projections 18 at its opposite ends, and a similar, but somewhat larger and oppositely extended, projection 20 intermediate its ends. Said base is 15 also formed with a relatively deep and wide groove, or well, 22 which extends almost the entire length thereof and within which the stationary and movable switch members are 20 adapted to be received.

The movable switch members for said starting and stopping switches A and B are 25 identical and comprise the oppositely extended switch arms 24, Figs. 5 and 6, which are made of flat sheet metal with their edges 30 vertically disposed and having their inner ends overlapping and arranged for independent pivotal movement in a vertical plane on a pivotal support comprising a pin or screw 35 which is screw threaded into a supporting 40 and terminal member 28 common to both of said switches. Said terminal comprises two angularly related arms 30 and 32. The arm 30 is horizontal and is secured to the top of the terminal supporting projection 20 of the insulating body 14 between shoulders 29 by 45 means of screws 33, which screws may be threaded into metal inserts moulded in the base 14 in a more or less usual way. The arm 32 depends vertically into the well 22 and is 50 suitably spaced from the side walls thereof whereby the movable switch arms 24 carried thereby are disposed within the longitudinal middle of said well. As shown particularly 55 in Fig. 7 the depending arm 32 of said terminal member 28 is formed with struck-out lips 34 one on either side of the pivot point. Said lips are arranged to engage the upper edges of said switch arms 24 when the latter are in their normal position, as shown in Fig. 60 and limit the upward movement thereof in a direction toward said cover 12. A similar struck-out lip 35 is provided beneath said switch arms 24 in position to engage an extension thereof and limit the movement of 65 said arms in the opposite direction. Said switch arms 24 are suitably off-set at their free ends to provide mutually aligned contact terminals or blades 36 which are adapted to be moved into and out of engagement with 70 cooperating stationary contact members in

said well 22 by the movement of arms 24 about their pivot 26.

Said stationary contact members comprise the substantially U-shaped metal contact clips 38 having their ends reflexed into confronting relation with each other to provide opposed resiliently supported contact faces between which said blades 36 are adapted to be engaged. Bolts 40 are passed through the bottom of said insulating base 14 and are threaded into the backs of said contact clips 38 whereby to attach them securely to said base. Each of said U-shaped contact clips 38 is adapted to be connected electrically with a control circuit and for this purpose terminal connectors are provided at each of said terminal supporting projections 18. Said connectors comprise metal straps having the reflexed horizontal end portions 42 (Fig. 3) which are clamped beneath and in conducting relation with said U-shaped contact clips 38 by said bolts 40, and intermediate vertical conducting portions 44 which extend along the side walls of the well 22 to the top thereof, and reflexed horizontal terminal portions 46 which lie between and are supported against lateral displacement by shoulders 48 which are provided at the top of the terminal supporting projections 18. Said terminal portions 46 and said common terminal 28 are 50 provided with suitable terminal clamping screws 50 as is customary. The stationary contacts above described are similar except that the contact for the stop switch B is mounted on an elevated supporting portion or ledge 52 at one end of the well 22 whereby in the normal position of the movable switch arms 24 the contact 36 of the stop switch is in engagement with its cooperating contact 38, while the contacts 36 and 38 of the starting switch A are free from engagement, as shown most clearly in Figs. 2 and 9.

Means are also provided to bias, the movable switch arms 24 constantly into the normal or unoperated position thereof, as shown in Figs. 2 and 5. That is, the upper or starting switch A is normally biased out of engagement with its cooperating stationary contact 38 and the switch B is normally biased into engagement with its cooperating stationary contact 38. To this end, the movable switch arms 24 are provided with radial angularly related arms 53 (Fig. 6) and are further provided with inwardly-directed, overlapping arms 54 which are arcuate in configuration. Preferably, the curve of said arms 54 conforms substantially to the circumference of a circle struck about the pivot 26 as a center. The arms 53 are adapted to extend slightly beyond the arcuate arms 54 whereby to provide abutments for the ends of a compression spring 56 which is disposed loosely about and is carried by the overlapped ends of said arms 54 and which constantly urges said arms 53 apart and consequently 100

urges the switch arms 24 against the abutments 34 of the terminal member 28.

Means are also provided for separately moving said switch arms 24 of the start and stop switches A and B against the bias of said spring 56 into or out of engagement respectively with their cooperating contact members. Said means comprise the insulating switch operating push-buttons 58 and 60, each having an operating post 62 moulded therein and pivotally connected at its free end to a switch arm 24 at 64, whereby upon depressing button 58 the switch arm 24 of the starting switch may be moved into engagement with its stationary contact member 38 and by depressing button 60 the contact member 24 of the stop switch may be moved out of engagement with its cooperating stationary contact member 38 and into a position where- 20 in it lies under the contact faces and between the resilient arms of the contact members. The spring 56 is adapted to return the movable switch arm 24 and its operating button in each case as soon as the hand of the operator is removed from the button, or as soon as the pressure thereon is removed. The free ends of the compression spring 56 act against and normal to the radial arms 53 at a point well removed from the pivot 26 and by this 25 advantageous application of the contact biasing force, sufficient force is exerted on the switch arms 24 to move them into and out of frictional engagement with their cooperating resilient contacts 38, whereby the contacts are 30 wiped or scoured at each operation of the switch and the faces thereof are maintained clean and free from oxide.

The insulating base 14 and the switch assembly mounted thereon is secured removably 40 within said casing 10 by means of a U-shaped supporting frame. Said frame, as shown in detail in Fig. 8, comprises a lower horizontal plate 66 which conforms with the rectangular bottom of said base 14 and an upper horizontal plate 68 having apertures 69 therein adapted to receive the push buttons 58 and 60 loosely therein. Said plate 68 has a vertically dependant leg 65, which is adapted to lie between the terminal supporting projections 18 of the base 14, the extended end of which is arranged to rest upon the upper face of plate 66 whereby to so space the plates 66 and 68 apart that the latter is somewhat elevated above the top of the insulating base 14. Said plate 66 is provided with a short up- 45 standing leg 69 which is adapted to overlie the lower end of said leg 65, and bolts 67 are passed loosely through the leg 69 and screw threaded into said leg 65, whereby to 50 secure said plates 66 and 68 together in spaced relation. Bolts 71 are extended through the base 14 and are screw threaded into said lower plate 66 whereby to secure the frame to the base. Said upper plate 68 is further pro- 55 vided with diagonally opposed outstanding

tabs 70 which are arranged to rest upon struck-out portions 72 provided at the sides of the casing 10 near the top thereof. Bolts 74 are passed through said tabs and struck-out portions whereby to fix said frame, and consequently said switch, removably to the casing 10.

In assembling the switch the lower plate 66 and the stationary contact are first secured to the insulating base 14. The movable switch 75 assembly (Fig. 5) is then placed in the well 22 of the base 14. The upper plate 68 is then placed in position and secured by the bolts 67. The switches can then be placed in operative position in the casing 10.

The apertures 69 in the plate 68 and the corresponding aligned apertures 76 in the cover plate 12 serve to guide the push buttons 58 and 60 substantially in a straight line. The push buttons when depressed are free to move inwardly until the radial arm 53 of said switch arms 24 engage the stop 35 on the terminal member 28. When the switch arm 24 of the starting switch A is thus depressed by its operating button 58 into abutting engagement with said stop 35 the stationary and movable contacts thereof are in engagement, while in the case of the stop switch B when the arm 24 is thus depressed the fixed contact clip 38 thereof is so positioned on the elevated block 52 of the base 14 that the movable contact 36 lies within the U-shaped sides but out of contact therewith, thus to open the circuit of the switch.

Fig. 9 shows diagrammatically the circuit connections for remote control of a motor 82 by means of the start and stop push button switches A and B embodying this invention. A line contactor 84 when energized closes the main line contacts 86 and 88 of the motor circuit and also completes a holding coil circuit comprising conductor 89, contacts 36 and 38 of the normally closed stop switch, conductor 90, auxiliary contacts 92 of the contactor 84, and solenoid winding 93. Said solenoid winding 93 is initially energized by depressing button 58 of the starting switch A to close contacts 36 and 38 thereof but due to the presence of the holding coil circuit, which is completed by the operation of the contactor 84, the start button may be immediately released. By depressing the stop button 60 the holding coil circuit is broken and the contactor 84 opens its contacts 86, 88 to interrupt the motor circuit, and also opens the auxiliary contacts 92 of the holding coil circuit. This is a more or less common arrangement for the remote control of electric motors and forms no part of the present invention, the invention residing in the novel construction of the remote control switch itself.

The cover 12 is secured detachably in place by a single screw 94 which passes loosely through the cover at one side of the vertical plane including the push buttons and is screw

threaded into the plate 68. The head of said screw has a second screw 96 screw threaded therein which is used to secure over the cover and push buttons a lock-out plate, not herein shown but claimed in my concurrently filed application Serial No. 288,726, when it is desired to lock the switch against operation.

Various modifications of the construction shown may be made without departing from the scope of the invention.

I claim:

1. In an electric switch the combination of a switch terminal, a pair of relatively movable switch members pivotally mounted on said terminal and electrically connected therewith, a circuit terminal for each of said movable switch members having a fixed cooperative contact member disposed in position to be engaged thereby, biasing means acting on said movable switch members at points spaced from the pivotal support therefor, and means to move said switch members separately against said biasing means.

2. In an electric switch the combination of a switch terminal, a pair of relatively movable switch members having a common pivotal connection with said switch terminal, a separate circuit terminal for each of said switch members having a fixed contact member disposed in position to be engaged thereby, biasing means comprising a spring having the opposite ends thereof each connected with a separate one of said movable switch members at points spaced from the pivotal support thereof, and means to actuate said movable switch members separately against the bias of said spring,

3. In an electric switch the combination of a switch terminal, a pair of relatively movable switch members having a pivotal support on said switch terminal, a pair of fixed circuit terminals having contact members disposed in position to be engaged by said movable switch members as they are moved about their pivots, biasing means for said movable switch members common to both of said switch members and carried by them independently of said switch terminal, and means to move each switch member separately against said biasing means.

4. In an electric switch the combination of a switch terminal, a pair of oppositely extended movable switch arms having overlapping ends and a pivotal support for said ends on said terminal, a pair of fixed circuit terminals having contact members, each of which is disposed in position to be engaged by a separate one of said movable switch members, and a common biasing means for said movable switch members supported entirely by and having an operative connection with said switch members at points spaced from the pivotal support therefor.

5. In an electric switch the combination of a switch terminal, a pair of relatively mov-

able switch members each having a pair of divergent arms, similar arms of said switch members having overlapping ends which have a pivotal support on said terminal, a fixed switch terminal for each movable switch member arranged to be engaged by one arm thereof, an abutment for each movable switch member, and means cooperating with the remaining arms of said switch members arranged to hold said switch members yieldably in engagement with said abutments.

6. In an electric switch the combination of two relatively movable switch members each having a pair of divergent arms, fixed circuit terminals disposed in position to cooperate with the similar arms of each movable switch member, means connecting the free ends of said other arms arranged to bias said movable switch members for movement about their pivots, and operating means for said movable switch members arranged to move them selectively against the said biasing means.

7. In an electric switch the combination of two relatively movable switch members having a common pivotal support, said switch members also having similar, oppositely directed contact arms and adjacent, angularly related radial arms, said radial arms having overlapping arcuate extensions, and a compression spring subtending the angle between said radial arms and disposed about said arcuate extensions and bearing against said radial arms whereby to bias said movable switch members for independent movement about their pivotal support.

8. In an electric switch the combination of two relatively movable switch members having a common pivotal support, said switch members comprising similar, oppositely-directed contact arms and adjacent, angularly-related radial arms provided with mutually overlapping arcuate extensions, an abutment for each of said movable switch members whereby to limit its pivotal movement, fixed circuit terminals having contact members arranged to cooperate with said contact arms, means to move said movable switch members selectively away from said abutments to control the engagement of said cooperating contacts, and means to bias said movable switch members against said abutments comprising a compression spring disposed on said overlapping arcuate extensions and having a bearing at its opposite ends against the homologous radial arms of said movable switch members.

9. In an electric switch, the combination of a pair of oppositely-extended pivoted switch arms having overlapping projections, and biasing means for said arms including a coil spring encircling and carried by said overlapping projections and arranged to urge said arms in opposite directions.

10. In an electric switch, the combination

of a pair of oppositely-extended pivoted switch arms having overlapping projections, and biasing means for said arms comprising a coil compression spring encircling and carried loosely by said overlapping projections and having its ends bearing against said arms, whereby to urge them in opposite directions.

11. In an electric switch, the combination of a pair of oppositely-extended pivoted switch arms having overlapping arcuate projections, and biasing means for said arms including a coil spring encircling and carried loosely by said arcuate projections and arranged to urge said arms in opposite directions.

12. In an electric switch, the combination of a pair of oppositely-extended concentrically pivoted switch arms having overlapping arcuate projections, and biasing means for said arms including a coil compression spring encircling and carried loosely by said arcuate projections and having its ends bearing against said arms, whereby to urge them for movement in opposite directions.

13. In an electric switch, the combination of a supporting plate, a pair of oppositely-extended switch arms having overlapping ends overlying and having a concentric pivoted connection with said plate, said plate having ears which overlie said arms on opposite sides of and above said pivotal connection, and also having a projection disposed between and in the path of movement of said arms and below said connection, which projection constitutes means to limit movement of said arms in one direction, and spring means acting on said arms to hold them yieldably against said ears.

14. In an electric switch, the combination of an insulating block having a deep and narrow well therein, a supporting plate having a horizontal portion carried by the top of said block and a vertical portion dependant within said well, fixed contact members located within said well on opposite sides of said supporting plate, a pair of oppositely-extended overlapping switch arms carried by said plate in said well in cooperative relation with said fixed contact members and having pivotal connection with said vertical portion of said supporting plate, spring means maintaining said switch arms yieldably in unoperated positions, and terminal members associated with said fixed contact members rising above said well and terminated therewithout.

15. In an electric switch, the combination of an insulating block having a well therein, stationary and movable switch members located in said well, push-buttons associated with said movable switch members upstanding above said block, a supporting plate overlying the top of said block having apertures therein through which said push-buttons are

extended loosely and having an extension overlying a side of said block, and a bottom plate underlying and secured to the bottom of said block having an upstanding projection which overlies the extension of said supporting plate, and means securing said extension and projection detachably together.

In testimony whereof, I have signed my name to this specification.

GEORGE W. O'KEEFFE.
